SIDE CLUTCH TYPE SLIDABLE SIDE JAW
WRENCH

Kenneth E. Finn, Omaha, Nebr.

Application March 19, 1953; Serial No. 343,399

1. Claim. (Cl. 81—165)

This application is a continuation in part of the applicant's copending patent application, titled "Clamping and Adjustable Means for Slidable Side Jaw Wrench," Serial No. 384,261, filed October 5, 1953, the latter application having been a continuation in part of the applicant's first wrench application, titled "Adjusting and Latch Means for Slidable Side Jaw Wrench," now Patent No. 2,657,607, issued November 3, 1953.

This invention relates to adjustable wrenches and more particularly it is an object of this invention to provide an improved wrench having jaws which clamp together.

Still another object is to provide a wrench having at least one movable jaw and a stationary jaw, a worm or other manual device to adjust the movable jaw, a lever or other mechanical torque-applying means; a clutch between the manual device and the torque-applying means, the clutch being engageable and disengageable to permit the mechanical torque-applying means to apply torque to the manual device or worm only at desired times, and to permit free manual operation at other times.

Yet a further object is to provide a wrench as described in which the worm rotates in union with an axle, and in which a lever is provided and is attached to the axle, the lever having a clutch means cooperative with clutch means on said axle whereby said lever can be used to rotate said axle only at desired times.

A further object is to provide an improved way of securing an axle to a worm in this type of a wrench.

Another object is to make possible the placing of the lever in a storage position alongside the handle at a time when the jaws are clamped upon an object.

Other and further objects and advantages of the present invention will be apparent from the following detailed description, drawings and claim, the scope of the invention not being limited to the drawings themselves as the drawings are only for the purpose of illustrating a way in which the principles of this invention can be applied.

Other embodiments of the invention utilizing the same or equivalent principles may be used and structural changes may be made as desired by those skilled in the art without departing from the present invention and the purview of the appended claim.

In the drawings:

Figure 1 is a side elevation of the wrench of

15 this invention, dotted lines showing an outer position of the movable jaw.

Figure 2 is an enlarged detail of the lever portion of the wrench with a portion of the lever broken away.

Figure 3 is an enlarged detail side view of an axle for the worm.

Figure 4 is a left end view of the axle of Figure 3.

10 Figure 5 is a cross section of the worm.

Figure 6 is a left end view of the worm.

Figure 7 is a right end view of the lever as seen along the line 7—7 of Figure 2, but with the lever completely shown.

15 A conventional slidable side jaw wrench is generally indicated by the numeral 10 in Figure 1 and has an elongated handle 12 having a head portion 14 attached to the handle 12 at one end thereof.

The head 14 has a fixed jaw 16 having a work engaging surface 18 which is disposed extending outwardly from the head 14.

20 The head portion 14 has a worm opening 24 extending generally transversely to the work engaging surface 18; and an adjusting worm 26 is provided in the opening 24. A slidable side jaw 28 is provided opposite the fixed jaw 16 and the slidable jaw 28 has a work-engaging surface 30. The surfaces 18 and 30 can have teeth 32 if desired.

25 As is old and well known, the slidable jaw 28 has a row of teeth 36 engageable by the worm 26 for manual control of the slidable jaw 28.

The worm 26 is mounted on an axle 40 constructed in accordance with this invention. The axle 40 has an innermost end portion 42 which is of a generally round shape in cross section but which has a side portion cut away for leaving a flat surface 44 for tightly fitting in a complementally shaped portion 50 of the wall of a center opening 54 of the worm 26. The portion 50 has a wall, best described as generally cylindrical which has an inwardly protruding portion 58 for engaging the flat surface of the axle 40.

30 The axle 40 has a portion 60 which is disposed centrally and to the right of the portion 42; the portion 60 being round in cross section and the worm 26 having a round right end portion 66 of complementary shape and size. As thus described, it will be seen that when the axle 40 is in the worm opening 54 a shoulder 68 on the axle will engage the right hand side of the protrusion 58.

A transverse opening indicated in dotted lines at 70 extends transversely into the axle 40 from

the flat surface 44 for receiving a spring 72. The latter urges outwardly on a ball 76 which fits in the outer end of the opening 70. The outer end of the opening 70 is peened inwardly around the outermost portions of the ball 76 to hold the ball in place. The ball extends partially outwardly of the opening 70 and is adapted to engage against the left hand side of the protrusion 58 for holding the axle in the worm.

The left hand end of the worm is provided with a large bore 84, preferably of greater diameter than the right hand portion 66 of the opening 54, the bore 84 forming a portion of the opening 54.

At its right hand end the axle 40 has a head portion 88 of larger diameter than the remainder, the head portion 88 being of cylindrical shape. To the left of the head 88 the axle 40 has a clutching portion 90 of a suitable clutching configuration of a non-round nature such as, for example, a square cross section as best seen in Figure 4.

In accordance with this invention the wrench is provided with torque-applying means such as a lever generally indicated at 92 having a portion at its end nearest the worm of a preferably cylindrical shape as shown at 96 in Figure 2. The end portion 96 has a hollow interior having a first portion 98 at the right hand end thereof which is of cylindrical shape for rotatably and snugly receiving the head 88 of the axle 40.

To the left of the cylindrical portion 98 is a clutching portion 100 of the hollow interior, the portion 100 having any suitable clutching configuration complementary to the clutching configuration of the portion 90 of the axle, preferably having the shape of an eight-pointed star as best seen in Figure 7. The configuration of the clutching portion 100 is in cross section the same as the outline of two squares disposed one on top of another, one square being at an angle of 90 degrees with respect to the other, and the squares each being of a size of the square cross section of the clutching portion 90.

It will be understood that the clutching configuration can be of any complementary shape engageable in at least one and preferably more rotational positions.

Referring to Figure 2, the interior of the end portion 96 has a portion 110 at its left hand end which is of cylindrical shape on its wall complementary to the portion 60 of the axle 40 for a snug rotatable fitting.

At the other end of the elongated lever 92 a bore 112 is provided for receiving a spring 114 and a ball 116 similar to that of the axle, the bore being longitudinally of the lever whereby the ball is urged toward a recess 120 in the adjacent side surface of a boss 122 which is attached to the side of the elongated handle 12 of the wrench at the end of the lever 92 for receiving the lever when it is in a position of rest.

When the wrench is assembled the worm 26 is put in place and the axle 40 is placed through the hollow interior of the end 98 of the lever as shown in Figure 1 and the axle 40 is caused to extend through an opening 150 in the head 14 which opening extends axially of the worm 26 and connects the opening 24 with a recess 152.

The recess 152 enters the head 14 from that side thereof which is adjacent the lever 92 and extends inwardly a short distance for receiving the left hand end of the head portion 96 of the lever. For this purpose the recess 152 has a cylindrical wall complementary to the exterior of the cylindrical end portion 96 of the lever 92.

The innermost end portion 42 of the axle 60 extends into a recess 170 which enters the head 14 from the other wall of the opening 24, the recess 170 being disposed axially of the worm 26 and being complementally shaped and of a size for rotatably receiving the end portion 42 of the axle portion 40.

As thus described, it will be seen that as shown in Figure 1 the wrench can be manually adjusted by the worm 26, and that a pulling of the lever 92 away from the worm 26 axially will cause the clutching wall 100 to engage the clutching portion 90 for the operation of the worm 26 by rotating the axle 40 with the lever 92.

Also, after the jaws have been set on an object it is possible to move the lever 92 inwardly whereby the clutching portions disengage and the lever can be rotated into a position for engagement of the ball 116 with the recess 120 to maintain the lever in a rest position.

It will be seen that a means for securing the lever 92 to the axle 40 is provided by the particular shape of the inner end of the lever and of the outer end of the axle. More particularly, the wall of the clutching portion 100 of the lever is of an eight-pointed star shape. The portions of the wall 100 which extend inwardly so constrict the opening at the clutch portion 100 as to be smaller than the comparatively larger head portion 88 of the axle 40.

Still more specifically, the head portion 88 is of a diameter complementary to the diameter of the cylindrical portion 98 of the lever, whereby the head portion 88 closely fits the cylindrical portion 98. Assembly is effected by passing the lever 92 over the inner end of the axle 40. Thereafter, the inner end of the axle 40 is inserted into the opening 150 in the head 14 of the wrench, through the worm 26 and into the recess 170.

Referring to Figure 7, it will be seen that the clutching portion 100 has a plurality of inwardly extending ridges. The distance from any one of these ridges to the diametrically opposite ridge is less than the diameter of the head portion 88 of the axle 40.

From the foregoing description, it is thought to be obvious that a side clutch type adjustable wrench constructed in accordance with my invention is particularly well adapted for use, by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice, except as claimed.

I claim:

In a slidable side jaw wrench provided with an elongated handle, a head portion attached to said handle at one end thereof, a fixed jaw protruding outwardly from said head portion, said fixed jaw having a work engaging surface, said head portion having a worm opening therethrough extending generally transversely to said work engaging surface; a slidable jaw cooperating with the stationary jaw for gripping an object, teeth on the slidable jaw extending into said worm opening; an adjusting worm disposed in said opening and cooperating with the movable jaw teeth in moving the movable jaw with respect to the stationary jaw, the axis of said worm being in parallelism with the sliding mo-

tion of said jaw, the improvement which consists of: an axle for the worm rotatably mounted in said head portion and extending from said worm through one side of said head; means locking said axle and worm together for simultaneous rotation of said axle and worm; a lever having an opening therethrough receiving the outer end of said axle which extends beyond said head; means for securing said lever to said axle, said lever and a portion of the exterior of said outer end of said axle having complementary clutching and de-clutching portions, whereby said lever can be engaged with said axle for applying torque thereto, or can be disengaged from said axle for

6
permitting the free manual movement of said worm at other times.
